FIG. 1

FIG. 2

FIG. 3

FIG. 1 represents a perspective view of the front and right side of an embodiment of this invention.

FIG. 2 portrays a perspective view of the front and right side of another embodiment similar to FIG. 1 but including an additional enclosure on the top.

FIG. 3 presents a perspective view of the rear and left side of the FIG. 2 embodiment.

The side not shown in FIG. 1 and the back thereof are like FIG. 3 but without the additional enclosure on the top.

This is a division of Design Application Ser. No. D. 25,659 filed Oct. 26, 1970.

I claim:

The ornamental design of a cabinet for data processing equipment, substantially as shown and described.
